[57] CLAIM

The ornamental design for a sandwich cooking and holding device, as shown and described.

DESCRIPTION

FIG. 1 is a perspective view of a sandwich cooking and holding device showing my new design;
FIG. 2 is a top plan view thereof;
FIG. 3 is a right side elevational view thereof;
FIG. 4 is a left side elevational view thereof;
FIG. 5 is a bottom plan view thereof;
FIG. 6 is a rear elevational view thereof;
FIG. 7 is a front elevational view thereof; and
FIG. 8 is a right side elevational view thereof in a partially opened position.

FIG. 1

FIG. 2

FIG. 3

FIG. 4
